ADAPTER

William N. de Sherbinin, Hastings-on-Hudson,
N. Y.

Application March 23, 1932, Serial No. 600,619

3 Claims. (Cl. 240—128)

This invention relates to lamps and shades therefor and more particularly relates to means for adapting the so-called bridge lamp shade fixture to a finial type lamp base which normally receives only a washer or spider type lamp shade fixture.

The invention consists essentially of an adapting device which may be readily attached to the bridge lamp shade fixture and which may be conveniently mounted on and secured to a finial type lamp shade base so that a bridge lamp shade may be used as a table or floor lamp shade or in other ways.

The nature of the invention, the objects thereof and the advantages to be derived therefrom will become apparent from the following description considered in connection with the accompanying drawing forming a part hereof and which illustrates a preferred form of my invention.

20 In the drawing:

Fig. 1 is a perspective view of a lamp shade and base embodying the invention;

Fig. 2 is a perspective view of the adapter of my invention;

25 Fig. 3 is a bottom plan view of the adapter;

Fig. 4 is an enlarged partial elevational view with parts in section, of a bridge type lamp shade mounted on a finial type base in accordance with my invention; and

30 Fig. 5 is a view similar to Fig. 4 with the adapter in reversed position.

Referring to the drawing, reference character 10 indicates a bridge type lamp shade having the usual bridge fixture indicated generally 11. The fixture comprises a ring 12 of wire or other suitable material and an inner annulus 13 which is connected to the ring 12 by spokes 14 extending radially from the annulus 13. As shown, the annulus consists of a cylindrical portion 15, threaded internally to screw on the external threads of the usual lamp socket, and a laterally extending concavo-convex flange 16 integral with the cylindrical portion. Other forms and types of annuli are used of course, but in general, all types will have an internally threaded cylindrical portion and some form of laterally extending flange such as shown.

The finial type base generally consists of a base (not shown) supporting a stand 17, the upper portion of which above the lamp sockets 25 is formed to provide a shelf 18 above which extends a stud 19 which is adapted to have threaded thereon a nut 20 usually of ornamental design.

As shown, the preferred form of adapter of my invention consists of a circular disk or member

21 of sheet metal of some resiliency and of sufficient thickness to provide rigidity for the disk. The disk is provided with a central aperture 22 having a diameter large enough to fit over the stud 19 of a finial type base. A plurality of equidistantly spaced lugs 23 preferably struck from the disk, are bent along the line at which they join the disk so as to extend laterally and at approximately right angles from the face of the disk 21 as shown. As clearly shown, the intermediate portion of each lug is bent or curved outwardly toward the periphery of the disk and the end portion is bent or curved to extend toward the axis of the disk at an angle of about thirty degrees. The outer surface of the intermediate portion of each lug, indicated 24, provides a bearing portion which is adapted to engage the internally threaded portion of the annulus 13 of the bridge fixture. The lugs, of course, possess a suitable degree of resiliency for the purpose intended. The lugs 23 are preferably disposed with their faces normal to the radii of the disk and on the circumference of a circle concentric with the center of the disk and of a diameter such that the bearing portions of the lugs press firmly against the inner cylindrical surface of the annulus. It will be understood that the disk 21 may be of any desired configuration, other than circular and may also be of any convenient thickness and of any suitable material. Likewise, the central aperture may be of any configuration other than circular, such as square, hexagonal or the like, without in any way departing from the spirit of the invention. The lugs 23 may conveniently be made separately from the disk and secured thereto in any suitable manner as by welding or the like and further may be disposed on the disk and shaped so that they engage any portion of the annulus of the bridge fixture other than the inner cylindrical threaded surface thereof as shown.

40 The adapter may be inserted in the annulus from the top so that the disk engages the upper portion of the annulus as shown in Fig. 4, or it may be inserted from the bottom so that the disk engages the lower portion of the annulus as shown in Fig. 5. The direction from which the adapter is inserted in the annulus may or may not make a material difference in the height of the shade on the base, depending upon the type of base to be used, that is to say, depending upon whether the extent of the shelf 18 is such that it engages the annulus or the disk. The adapter may be used with any finial type base.

45 It will be apparent from the foregoing that to 50

adapt a bridge lamp shade fixture so that it may be mounted on a finial type base, it is merely necessary to press the adapter of my invention into engaging position with the annulus of the bridge fixture. The bridge shade may then be mounted and secured on a finial type base.

It will be understood that the form of the invention herein disclosed is a preferred form only and that many changes may be made in the adapter shown and described without departing from the spirit or scope of the invention. The invention is not intended to be limited except by the scope of the appended claims.

What I claim is:

1. In combination with a bridge lamp shade fixture having an annulus provided with threads on its inner cylindrical portion, an adapter comprising a disk having a central aperture adapted to receive the stud of a finial type lamp base and a

plurality of lugs disposed about said aperture and engaging the threaded portion of the annulus.

2. In combination with a bridge lamp shade fixture having an annulus provided with threads on its inner cylindrical portion, an adapter comprising a flat circular disk having a central aperture adapted to receive the stud of a finial type lamp base and a plurality of lugs disposed about said aperture and engaging the threaded portion of the annulus.

3. In combination with a bridge lamp shade fixture having an annulus provided with threads on its inner cylindrical portion, an adapter comprising a flat disk having an aperture adapted to receive the stud of a finial type lamp base and a plurality of lugs extending outwardly of one side of the disk and engaging the threaded portion of the annulus.

WILLIAM N. DE SHERBININ.
